FLUSH VALVE

Emil Price and William A. Pfister,
Los Angeles, Calif.

Application May 27, 1932, Serial No. 614,022

1 Claim. (Cl. 251—156)

This invention relates to flush valves, sometimes referred to in the art as ball cocks, the same adapted for use in connection with the filling tanks of closet bowls and the like, and an object of the invention is to provide a novel valve organization for admitting water to the tank in a manner that will greatly reduce if not entirely eliminate, the noise which usually attends the process of replenishing the tank with water from the intake pipe of a supply system, as is necessary following the discharge of water from the tank in the flushing operation.

An important feature of the invention resides in the novel combination of parts employed in the organization, the simplicity thereof and their functional characteristics, all of which contribute to make the device noiseless, positively acting and of such construction that it will withstand the abuse to which such mechanisms are usually subjected.

In the accompanying drawing,

Figure 1 is a view of the invention partly in vertical section and partly in elevation;

Figure 2 is a section taken approximately on line 2—2 of Figure 1;

Figure 3 is a perspective view of the valve guide or thimble;

Figure 4 is a sectional view through a portion of the plunger showing the elastic valve disk closed against its co-acting seat.

In carrying the invention into practice, use is made of a chamber member 5 having a cylindrical portion 6 open at one end as at 7 and closed at its opposite end by an integral cap wall 8, the latter having an intake opening 9, the walls of which are undercut at 10 to accommodate a correspondingly formed flange 11 of a cylindrical valve seat 12. The said cap wall 8 is formed with a short cylindrical extension 13 which threadedly accommodates one end of a water supply pipe 14, the latter adapted to form a part of any conventional plumbing system by means of which water at a normal city pressure can be conducted to the filling tank of a flushing system, which said filling tank may be of any suitable well known construction. Interposed between the flange 11 of the valve seat 12 and the adjacent end of the intake pipe 14 is a sealing gasket 15.

The construction of the cylindrical portion of the chamber member is such that same is formed with a straight bore 16, the same being preferably of equal diameter throughout. This bore extends from the open end 7 of the chamber member to the closed cap end 8 thereof. It

is concentric with respect to the valve seat. The diameter of said bore is also appreciably greater than the external diameter of the valve seat. It will also be noted that the valve seat extends into the bore and that same has an annular relatively sharp edge 17 positioned at one side of the inner flat face 18 of the cap end 8 of said chamber member. The purpose of these characterizing features of the parts just referred to will obviously appear as the description proceeds.

Driven tightly into the bore 16 of the aforementioned chamber member is a metallic thimble or valve guide 19, the same being of cylindrical construction and provided with a portion 20 whose external diameter is sufficiently greater than the portion 21 of said thimble, so that the walls of said portion 21 are spaced apart externally from adjacent walls of the bore 16, whereby to produce therewith an intervening annular space 22 which communicates at one of its ends with the main portion 23 of an outlet chamber. Virtually, the said annular space and the said main portion 23 of the chamber mutually define a chamber which is exteriorly positioned relative to the thimble or valve guide 19, and as illustrated the chamber member is provided with an outlet 24 which opens into the aforementioned portion 23. Said outlet has threaded connection with a discharge pipe 25, by means of which water is adapted to be admitted to a filling tank. The portion 23 is located approximately at a point medially of the respective ends of the said chamber member and, as illustrated, the free edge of the portion 21 of the thimble 19 comes in resting contact with the wall 18 of the said cap portion 8, and at this point the said portion 21 is formed with any suitable number of orifices 26.

Extending from the chamber member 5 is a post 27 to which one end of a tilting lever 28 is pivoted. This lever passes through an aperture 29 in the reduced stem portion 30 of a cylindrical plunger-like valve 31. The lever then passes through a guide 32 which extends from the chamber member 5 and its opposite extremity finds pivotal connection at 33 with a link 34. This link has pivotal connection at 35 to the short arm 36 of a rocker arm 37. The arm 37 is pivoted at 38 to rock from the upper extremity of the guide 32 and at 39 said rocker has connection with a float arm 40. The float arm may be of any suitable well known construction capable of supporting at a free extremity a float of such form that it will rise and fall in the filling tank.

during the ordinary operations of such flushing systems as those herein referred to.

The plunger-like valve 31 may be constructed of any suitable well known metal, such as brass, and the length thereof is approximately the same as that of the bore 6. The diameter of the plunger is so calculated with respect to the internal diameter of the thimble 9 that a comparatively snug fit of the plunger is had with the internal walls of said thimble. At a point between its ends, the said plunger is provided with an annular gasket 41 which is presented constantly against the internal walls of the thimble so as to prevent leakage through the space between the thimble and the plunger. The end of the plunger which is positioned in the thimble and which is intended to co-act with the valve seat 12 is channeled out or suitably cored so as to accommodate an elastic valve disk 42, the diameter of which is greater than the external diameter of said valve seat. The flat face 43 of the valve disk is adapted to engage against the relatively sharp edge 17 of said valve seat when the plunger 31 is in its closed position.

From the construction described, it is now stated that the position of the plunger 31 as shown in Figure 1 is indicative of the full lowered position of the float arm 40, such as when the filling tank has been entirely emptied. In other words, the position of the plunger as shown in Figure 1 illustrates the limit of its movement in a direction away from the portion 17 of the co-acting valve seat. It consequently follows that water discharging into the member 5 through the bore of the valve seat has its flow intercepted by the flat face 43 of the valve disk 42, the latter preferably formed of rubber, and that the water is compelled to be deflected and to be urged in the direction of the flat face 18 of the cap end 8 of the member 5, at which time it finds ingress to the annular space 22 between the external surface of the portion 21 and the adjacent walls of the bore 16, the water taking this course by virtue of the orifices 26. The water is thus first discharged into the structure in a direction which is longitudinal of the thimble 9 and the flow is then somewhat restricted and made to take a lateral course before it can proceed into the outlet pipe 25. By compelling the water to take this sinuous course and by reducing the velocity at the flat face 43 of the valve disk 42, it is possible to provide an organization which is almost, if not entirely, noiseless in action. It is found also that a relatively large space can be formed between the external walls of the portion 21 and the adjacent walls of the bore 6, so as to not unduly retard the movement of the water in its path to the filling tank and at

the same time produce a device which is almost entirely noiseless.

It follows from the construction herein set forth that some liquid is always retained in the member 5 following each successive flushing operation. The space between the bottom face 43 of the disk 42 and the face 18 of the cap end 8 of said member 5 will remain filled with liquid at all times and the annular space between the walls of the constricted end 21 of the thimble 9 and the adjacent walls of the bore 16 will always be filled with liquid. This is because of the fact that the upper end of the valve seat 12 occupies a position slightly above the upper ends of the orifices 26. In this manner, a small head of liquid is held sealed in the structure, only to be evacuated therefrom during the flushing operation, but then to be replaced by a new body of liquid as the flushing operation discontinues and the plunger 31 returns to its closed position. An automatic trapping of liquid within the structure is thus made possible and it is thereby possible to cushion the movement of the plunger and to avoid the objectionable hissing effect ordinarily due to an inrush of air over the lane of travel 25 of the liquid as the liquid proceeds to the outlet when the valve seat is uncovered.

The length of the plunger relative to that of the thimble in which it slides may be precalculated; the extent of projection of the valve seat 30 relative to the orifices 26 may likewise be pre-calculated; and the size of the annular flow space between the thimble and the aforementioned adjacent walls of the bore 16 proportioned, so that in consideration of these several factors the 35 rate of flow of the liquid may be made to determine the speed with which the filling tank is supplied with liquid.

What is claimed is:

A valve organization comprising a member 40 having a vertical chamber provided with a liquid intake at its lower end and an outlet intermediate of its ends; a seat at said intake; a thimble passing into the chamber from the upper end thereof; a valve adapted to operate in 45 said thimble and to coact with the seat to respectively cover and uncover the latter; the thimble having a lower portion whose external face is spaced apart from the walls of the chamber to provide a liquid space extending from the 50 lower end of the chamber to said outlet, and having orifices opening toward said seat; the seat extending in a vertical direction into the chamber and spaced apart from the orifices and co-acting with the liquid space to provide a liquid 55 well in said space and around said seat.
